(57) **CLAIM**

The ornamental design for a lighter as shown and described.

DESCRIPTION

FIG. 1 is a top perspective view of a lighter showing a first embodiment of my new design.

FIG. 2 is a bottom perspective view thereof.

FIG. 3 is a right elevational view thereof.

FIG. 4 is a left elevational view thereof.

FIG. 5 is a front elevational view thereof.

FIG. 6 is a rear elevational view thereof.

FIG. 7 is a top plan view thereof.

FIG. 8 is a bottom plan view thereof.

FIG. 9 is a top perspective view of the lighter showing a second embodiment of my new design.

FIG. 10 is a bottom perspective view thereof.

FIG. 11 is a right elevational view thereof.

FIG. 12 is a left elevational view thereof.

FIG. 13 is a front elevational view thereof.

FIG. 14 is a rear elevational view thereof.

FIG. 15 is a top plan view thereof; and,

FIG. 16 is a bottom plan view thereof.

The broken lines in the drawings depict portions of the lighter that form no part of the claimed design.

1 Claim, 8 Drawing Sheets
